UNITED STATES PATENT OFFICE

ERWIN BURNS, OF LOS ANGELES, CALIFORNIA, ASSIGNOR TO BAASH-ROSS TOOL COMPANY, OF LOS ANGELES, CALIFORNIA, A CORPORATION OF CALIFORNIA

WELL CASING HEAD

Application filed July 10, 1930. Serial No. 467,353.

This invention relates to a head adapted to be applied to the upper end of a well casing. It is a general object of the invention to provide a simple and practical head for application to the upper end of a well casing that is adaptable to pack off around objects of various sizes extending into the well casing.

It is an object of the invention to provide a head for use on the upper end of a well casing that embodies means that is adaptable to pack off around objects of various sizes such as drill pipe, well tubing, etc., and which embodies improved means for supporting objects of various sizes such as strings of drill pipe and strings of oil tubing.

Another object of the invention is to provide a well casing head of the character mentioned that embodies a bonnet that may be easily and quickly positioned to trap or catch fluid discharged from a string of oil tubing extending through the casing or from the well casing and to pass it into a suitable discharge conduit.

It is another object of the invention to provide a head of the character mentioned that is adapted to carry packing assemblies or devices for packing around either a string of pipe or oil tubing and which includes means for actuating or compressing such packing devices.

It is another object of the invention to provide a casing head of the character mentioned that is sturdy and dependable, and that is capable of withstanding or holding high gas pressures to prevent the well from blowing out.

It is a further object of the invention to provide a casing head of the character mentioned that may be easily and quickly converted from a casing head for packing off around and supporting a string of drill pipe extending through a well casing to a tubing head for packing off around and supporting a string of oil tubing extending into the casing.

Other objects and features of the invention will be best and more fully understood from the following detailed description of typical forms and applications of the invention, throughout which description reference

is had to the accompanying drawings, in which:

Fig. 1 is a vertical detailed sectional view of the head provided by this invention, illustrating a length of oil tubing extending through the body and showing the bonnet in position on the body. Fig. 2 is a vertical detailed sectional view of the head showing it in sealing and supporting engagement with a length of drill pipe and illustrating it with the bonnet removed. Fig. 3 is a transverse detailed sectional view taken as indicated by line 3-3 on Fig. 1, and Fig. 4 is an enlarged vertical detailed sectional view of a portion of a packing assembly taken as indicated by line 4-4 on Fig. 1 illustrating the mounting of one of the latches embodied in the assembly.

In Figs. 1 and 3 of the drawings I have illustrated an oil tubing extending through the head and have illustrated the packing and supporting means in operative engagement with the tubing. The bonnet embodied in the invention is illustrated on the head to receive fluid discharged from the oil tubing or from the well casing. In Fig. 2 of the drawings a drill pipe P is illustrated extending through the head, and packing means and supporting means are shown in operative engagement on the pipe.

The application of the invention illustrated in Figs. 1 and 3 of the drawings includes, generally, a body 10 adapted to be applied to the upper end of a well casing C, a packing assembly 11 arranged in the body 10 and operable to seal around an object extending through the body such as a length of oil tubing T, a spider 12 for actuating the packing assembly 11, means 13 carried by the spider 12 for supporting the oil tubing T, and a bonnet 14 on the body 10 to receive and confine fluid discharged through the oil tubing T, or the casing C in the event that the well blows out when there are no tools, or the like, in the casing.

The body 10 is tubular, having a central longitudinal opening 15 for passing well drilling tools, oil tubing, etc. A downwardly and inwardly tapered shoulder or seat 16 is provided in the opening 15 for carrying the

packing assembly 11. The body 10 may be mounted on or connected with the well casing C in any suitable manner.

In the particular case illustrated in the drawings the lower portion of the opening 15 is screw threaded to receive the upper end of the casing C. Fluid discharge conduits 17 communicate with the opening 15 below the tapered shoulder 16. The upper portion 19 of the opening 15 is enlarged to receive the spider 12 as will be hereinafter described. A radially projecting annular flange 20 is provided on the body 10. The flange 20 is provided to carry the bonnet 14 and is spaced a short distance below the upper end of the body. The flange 20 may be comparatively heavy and may be integral with the body 10.

The packing assembly 11 for packing off around the tubing T is such that it may be quickly and easily arranged in operative position in the opening 15 in a position to be actuated by the spider 12 to seal with the tubing T and the walls of the opening 15. In accordance with the broader principles of the invention any suitable type of packing device adapted to pack around the tubing T may be arranged in the head. In the preferred embodiment of the invention an improved type of packing assembly 11 is arranged in the opening 15 of the body 10.

The packing device or assembly 11 is preferably longitudinally split into two or more sections so that it may be readily assembled around the tubing T. The assembly 11 includes a body of compressible and expandable packing 21 and collars 22 and 23 at the upper and lower ends, respectively, of the packing 21. The packing 21 and the collars 22 and 23 are proportioned to normally slidably fit the opening 15. The exterior of the lower collar 23 is tapered downwardly and inwardly to seat on the shoulder 16 to support the assembly 11 in the opening 15. The annular body of packing 21 is adapted to be expanded 45 to effectively seal with the tubing T and the walls of the opening 15. Wedge projections 25 are provided on the inner sides of the collars 22 and 23 to effectively expand the packing 21 radially upon actuation of the assembly. The wedge projections 25 extend into grooves 26 in the body of packing 21 and are formed so that they expand the packing 21 radially inward and radially outward into sealing engagement with the tubing T and 55 the walls of the opening 15.

The packing assembly 11 is preferably proportioned so that the upper collar 22 projects upwardly into the enlarged portion 19 of the opening 15. Latches 27 are provided on the collar 22 to be engaged by the spider 12 to compress or actuate the assembly 11. The latches 27 are pivotally mounted in recesses 28 in the upper side of the collar 22 and their outer ends normally project outwardly from 65 the periphery of the collar 22. The latches

27 are pivotally mounted on the collar 22 so that they are shiftable to substantially vertical or upright positions upon the assembly being lowered into the opening 15, and means is provided for automatically returning the latches 27 to the horizontal position where they project from the collar 22 at the lower end of the spider 12 when the assembly is seated in the opening 15. Torsional springs 28^a are provided at the pivotal connection of the latches 27 to normally yieldingly hold the latches in the horizontal position and to automatically return the latches to the horizontal position upon the assembly 11 being lowered to a position where the collar 22 is below the lower end of the spider 12.

The spider 12 is provided to actuate or compress the packing 21 of the packing assembly 11 and to support the tubing suspending means 13. The spider 12 is a tubular member screw threaded into the enlarged portion 19 of the body opening 15. The lower portion 29 of the opening in the spider 12 is of substantially the same diameter as the opening 15 so that it is adapted to pass the well drilling tools and the packing assembly 11. The upper portion 30 of the opening through the spider 12 is tapered downwardly and inwardly to carry the tubing suspending means 13 as will be hereinafter described. Openings 31 may be provided in the spider 12 to receive suitable tools for actuating or threading the spider into the opening 19. The lower end of the spider 12 is adapted to engage the latches 27 upon threading of the spider downwardly into the opening 15.

The means 13 for supporting or suspending the oil tubing T includes slips 31^a for engaging the tubing T. In accordance with the invention the upper portion 30 of the opening in the spider 12 is proportioned to carry slips or suitable means for supporting drill pipe or other objects larger than the tubing T, and the means 13 includes a bushing 33 to be arranged in the tapered portion 30 of the opening in the spider to carry the slips 31^a. The bushing 33 may be sectional and its exterior is shaped to effectively seat in the tapered portion 30 of the spider opening. The bushing 33 is provided with a downwardly and inwardly converging opening 34 for carrying the slips 31^a. Screw threaded openings 35 may be provided in the upper end of the bushing 33 for receiving suitable lifting tools to facilitate handling of the bushing. Any suitable type of tubing slips 31^a may be arranged in the opening 34 to engage and support the tubing T.

The bonnet 14 is adapted to be mounted on the body 10 after the packing assembly 11 and the means 13 have been arranged in operative position around the tubing T. The bonnet 14 is provided to control or confine the fluid discharged under pressure from the upper end of the oil tubing T or from the well

casing C. The bonnet 14 is in the nature of a tubular hood-like member and is adapted to be supported on the flange 20 in a position where it covers or encases the upper end 5 of the body 10, the spider 12, and the upper projecting end of the tubing T. An outwardly projecting annular flange 36 is provided at the lower end of the bonnet 14 to seat on the flange 20. The flanges 20 and 36 may be 10 detachably connected by suitable bolts 37.

In accordance with the preferred form of the invention means is provided to form a fluid pressure tight seal between the flanges 20 and 36. In the particular case illustrated 15 the means for sealing between the flanges 20 and 36 includes annular grooves 38 in the lower side of the flange 36. Suitable packing may be arranged in the grooves 38 and annular projections or ribs 39 are provided 20 on the upper side of the flange 20 to extend into the grooves 38 to compress the packing in the grooves.

The bonnet 14 projects upwardly some 25 distance above the spider 12 and the upper end 40 of the bonnet is of reduced diameter for connection with a fluid conduit. A fluid discharge conduit may be connected with the reduced upper end 40 of the bonnet in any suitable manner. In the particular case illustrated 30 in the drawings a conduit 41 is screw threaded onto the reduced portion 40.

In Fig. 2 of the drawings a drill pipe P is shown extending through the opening 15 of the body 10. A packing assembly 11^a similar to the packing assembly 11 described above may be arranged in the opening 15 to pack around the pipe P. The packing assembly 11^a is proportioned to effectively operate in the opening 15 to seal around the drill pipe 40 P. The spider 12 may be employed to engage the latches 27^a at the upper end of the assembly 11^a to actuate the packing 21^a of the assembly.

The drill pipe P may be supported on the 45 head by suitable slips 50 arranged in the tapered upper portion 30 of the opening in the spider 12. When the casing head construction provided by the present invention is employed to pack around and support a string of drill pipe P, the bonnet 14 may or 50 may not be arranged on the body 10. In the event that the well is produced through the drill pipe P, that is, in the event that fluid 55 is discharged from the upper end of the pipe P, the bonnet 14 may be arranged on the body to control the discharge.

It will be obvious how the packing assembly 11^a may be assembled on the drill pipe P 60 and lowered into the opening 15 to a position where the latches 27^a are adapted to be engaged by the spider 12. The spider 12 may be threaded into the enlarged portion 19 of the opening 15 to engage the latches 27^a and 65 actuate the packing of the assembly 11^a. The

slips 50 may be readily positioned in the spider 12 to support the drill pipe P.

It is to be noted that the invention provides a casing head assembly for use on the upper end of a well casing that may be easily 70 and quickly converted from a casing head for packing around and supporting a drill pipe P to a tubing head for supporting and packing around oil tubing T and for receiving fluid discharged from the oil tubing, etc. 75 The body 10 of the head is of particularly simple construction and does not include parts that may hinder operations when the device is employed to pack off around a drill pipe. The spider 12 is adapted to actuate 80 either a packing assembly 11^a for sealing with a drill pipe P or a packing assembly 11 for sealing with an oil tubing T. The invention provides means whereby the spider 12 is adaptable to support either a string of 85 drill pipe P or a string of oil tubing T. The bonnet 14 is of particularly simple construction and may be easily and quickly positioned on the body 10.

Having described only typical preferred 90 forms of my invention, I do not wish to limit myself to the specific details set forth, but wish to reserve to myself any changes or variations that may appear to those skilled in the art or fall within the scope of the following claims:

Having described my invention, I claim:

1. A head adapted to be applied to a well casing including, a body having an opening, a spider threaded into the upper end of the 100 opening, a packing device adapted to be lowered through the spider to a position in the opening, a latch on the packing device adapted to operate past the spider to a position below the lower end of the spider when the packing device is lowered into the opening, and means carried by the spider for supporting an object extending through the opening.

2. A head adapted to be applied to a well 110 casing including, a body having an opening adapted to pass an object, a spider threaded to the body and extending into the upper end of the opening, a packing assembly adapted to be lowered through the spider into the 115 opening, a plurality of latches pivotally mounted on the assembly adapted to be operated past the spider to positions in the opening where they are engageable by the spider, and means on the spider for supporting an object.

3. A head adapted to be applied to a well casing including, a body having an opening adapted to pass an object, a spider threaded to the body and extending into the upper end of the opening, a packing assembly adapted to be lowered through the spider into the opening, the packing assembly being operable through compression to seal about 125 an object extending through the body, a latch 130

on the assembly adapted to be operated past the spider to a position in the opening where it is engageable by the spider to cause actuation of the packing assembly, and means 5 removably mounted on the spider for supporting an object extending through the opening.

4. A head adapted to be applied to a well casing including, a body having an opening, 10 a spider threaded into the upper end of the opening, a packing device adapted to be lowered through the spider to a position in the opening, a latch pivotally mounted on the packing device adapted to operate past the 15 spider to a position below the lower end of the spider when the packing device is lowered into the opening, and means carried by the spider for supporting an object extending through the opening.

20 5. A head adapted to be applied to a well casing including, a body having an opening for passing an object extending into the casing, a spider screw threaded into the upper end of the opening, a packing assembly 25 adapted to be lowered into the opening through the spider, the assembly including expansible packing and means for expanding the packing to seal around an object upon a compression strain being put on the assembly, a latch on the assembly adapted to 30 operate past the spider when the assembly is lowered into the opening to a position where it is adapted to be engaged by the spider to actuate the said means, and means 35 carried by the spider for supporting an object extending into the opening.

6. A head adapted to be mounted on a well casing including, a body having an opening, 40 the upper portion of the opening being enlarged, a tubular spider screw threaded into the enlarged portion of the opening, the internal diameter of the spider being substantially the same as the diameter of the opening, a packing assembly adapted to be passed 45 through the spider into the opening, and a latch on the assembly adapted to be operated past the spider when the assembly is passed through the spider to a position in the enlarged portion of the opening where it is 50 adapted to be engaged by the spider.

7. A head adapted to be mounted on a well casing including, a body having an opening, 55 the upper portion of the opening being enlarged, a tubular spider screw threaded into the enlarged portion of the opening, the internal diameter of the spider being substantially the same as the diameter of the opening, a packing assembly adapted to be passed 60 through the spider into the opening, a pivotally mounted latch on the assembly projecting from the assembly into the enlarged portion of the opening when the assembly 65 is in the opening so that it is adapted to be

engaged by the spider, and means on the spider for supporting the object.

In witness that I claim the foregoing I have hereunto subscribed my name this 28th day of June, 1930.

ERWIN BURNS.
